UNITED STATES PATENT OFFICE.

HERMAN FRASCH, OF CLEVELAND, OHIO, ASSIGNOR TO THE UNITED SALT COMPANY, OF CLEVELAND, OHIO, A CORPORATION OF OHIO.

MINING SALT.

No. 874,907.

Specification of Letters Patent.

Patented Dec. 24, 1907.

Application filed November 13, 1899, Serial No. 736,841. Renewed May 20, 1907. Serial No. 374,725.

To all whom it may concern:

Be it known that I, HERMAN FRASCH, a citizen of the United States, residing at Cleveland, in the county of Cuyahoga and State of Ohio, have invented certain new and useful Improvements in Mining Salt; and I do hereby declare the following to be a full, clear, and exact description of the invention.

10 This invention relates more particularly to the recovery of common salt from a natural (usually subterranean) deposit, by the aid of an aqueous solution, which is formed in said deposit and is thence removed to the surface of the ground, and from which the salt is separated; but it extends to the recovery of any saline or non-saline substance soluble in water from a natural deposit.

20 It has long been customary in this art, in order to form such solution, to introduce water at ordinary temperature into the salt-bed or deposit; but in a concurrent application (No. 705,604, filed February 16, 25. 1899), I have described and claimed (among other things) a process in which unsaturated brine at superatmospheric temperature is introduced into the salt-bed in order to become saturated, and in which the 30 brine, still above atmospheric temperature, is on removal from said bed subjected to a partial evaporation at the expense of the heat stored therein, with or without the aid of heat from an outside source or 35 sources. By this partial evaporation, salt is precipitated, and the unvaporized (residual) brine is reduced in temperature. The salt is collected for sale or use; and the residual brine is heated and diluted for 40 return to the salt bed.

There are advantages in avoiding a resort to other heat than that which is in the brine from the salt deposit previous to its removal therefrom, even in aid of the evaporation at the expense of the stored heat; but if resort be not had to such outside heat, then the evaporation removes so small a fraction of the water present that the unsaturated brine which is formed by the heating and dilution of the residual brine is of a high percentage of salt saturation; for (apart from an increase in the volume of liquid in the deposit) the water of dilution should not exceed the water of evaporation; since otherwise the volume of residual brine above

ground would increase, which is not desirable after a proper working volume has been secured. Where the cavity in the deposit is large, no difficulty is presented by the use of brine so nearly saturated; but I have discovered that its solvent action is so slow as to impair its usefulness for newly opened deposits, or for those in which the cavities are comparatively small.

In the present invention, evaporation by heat from another source or sources is resorted to in aid of the heat in the brine at the time of its removal from the deposit; but by utilizing a circulation of residual brine above ground as a carrier of the additional heat as hereinafter explained, in conjunction with the introduction into the deposit of the aqueous solvent free from salt or less nearly saturated therewith and (in either case) at superatmospheric temperature, not only can the salt be recovered from deposits in general with advantage over the old salt-mining process using water at atmospheric temperature, and also over a process without such above-ground circulation although using an aqueous solvent of superatmospheric temperature and free from salt or less nearly saturated therewith, but it can also be recovered from newly opened deposits or those with comparatively small cavities with advantage over a process in which all the residual brine is heated and diluted for return to the deposit and in which consequently the unsaturated brine introduced into the deposit has the high percentage of salt saturation hereinabove mentioned. The present invention extends, however, in part, to working deposits of any size of cavity (however large or however small) by means of unsaturated brine of any strength, even brine so nearly saturated as that which obtains when the brine from the salt bed is evaporated at the expense of the heat in the said brine before its removal from the salt bed, without the aid of heat from an outside source, and when all the residual brine from such evaporation is returned to the salt-bed.

In my before-mentioned application, reference is made to an above-ground circulation of residual brine as a carrier for heat, in connection with the introduction into the deposit of a heated aqueous solution consisting of pure water or of unsaturated brine, and also in connection with a recovery of salt by an evaporation at the expense of heat

stored partly in the brine from the deposit and partly in the residual brine of the above-ground circulation; this matter, while within the general scope of certain claims of my 5 said application, is specifically claimed herein; and as to it and any other matter (if any there be) so claimed herein and referred to in the application the present 10 patent may be considered as supplementary of that on my said application.

The present invention consists also in additional improvements as herein set forth.

One such additional improvement consists in utilizing water comparatively free from 15 salt as the solvent after a proper working volume of brine has been secured until the cavity in the deposit is enlarged, and afterwards introducing water containing a larger proportion of salt into the enlarged cavity.

20 Another additional improvement consists in promoting the evaporation of brine by transfer of heat thereto through heat-conducting walls from steam condensed by said transfer, and maintaining the supply of said 25 brine by addition thereto of hot brine from the mine, formed by the introduction into the mine of the hot water of condensation from said steam. Thus not only are both 30 the latent and the sensible heat of the steam utilized in promoting the evaporation, but the sensible heat is further utilized in increasing the yield of salt by enabling a given amount of water to dissolve and carry off more salt from the mine. The brine to be 35 evaporated can (under this improvement) not only be that of an above-ground circulation (as above described) but it can also in whole or in part be any other suitable body of brine, as for example the brine in an open 40 steam heated pan, or in a closed steam heated pan with the brine therein under atmospheric, sub-atmospheric or super atmospheric pressure.

A further improvement consists in heating 45 a body of brine, more especially a body of residual brine in circulation (above ground or through the mine), by means of the exhaust steam from another body of evaporating brine itself heated by steam, and maintaining 50 the supply of both bodies by addition to each of hot brine from the mine formed by the introduction into the mine, with or without residual brine, of the hot water of condensation from the steam which heats each 55 of said bodies of brine (and which may in part be condensed directly in residual brine when this is introduced into the mine). When the circulation of residual brine is wholly above ground it is heated by surface condensation of the steam; when all, or even if 60 only a part, of the residual brine is circulated through the mine, it can be heated by surface condensation or by direct (injection) condensation of the steam therein. In any 65 case however, under this improvement, water

which is vaporized from brine obtained from the mine and which retains heat imparted to it for vaporization is returned again to the mine to take up a new supply of salt.

By an exposure of the brine of not too great temperature unsupported in small drops distributed throughout a large room filled with an evaporation-promoting atmosphere, the residual brine of the circulating system can be obtained so far below 135° F., 75 which is about the practical lower limit of working of a vacuum salt pan, and also about the temperature of the exhaust steam of a condensing engine, as to serve as a condensing liquid for such pan or other steam-yielding vacuum apparatus, the water of condensation of said vacuum steam to be introduced into the mine, with or without residual brine according to the mode of working. The 80 combination of vacuum evaporation or other source of vacuum steam with a circulating evaporation system, and the supply to both systems of hot brine formed in the mine at least in part from the water of condensation of the vacuum steam, constitutes another of 85 the said additional improvements.

Another additional improvement consists in raising the temperature of the residual brine circulating above ground by the surface condensation of steam in chambers 90 jacketed or bathed by said brine, introducing the water from said condensation, at superatmospheric temperature, and with or without a portion of the residual brine, into the salt deposit, removing the brine formed 100 by the solvent action of the water or the unsaturated brine on the salt in said deposit, separating salt by an evaporation of brine at the expense of heat stored in the two supplies of brine, and uniting the two streams before 105 or after the evaporation. When the two streams are united before evaporation, the water from both is vaporized indiscriminately; but where the evaporation takes place before union, a part of the particular 110 brine from the salt bed will be evaporated, and the remainder of such brine will be added to the above-ground circulation, a part of the brine of which will be evaporated also.

In the accompanying drawings which form 115 part of this specification, Figure 1 is a diagram partly in elevation and partly in vertical section of a salt-mining apparatus or plant which may be usefully employed in carrying out the invention; Fig. 2 is a similar diagram partly in plan and partly in horizontal section on line C C of Fig. 1; Figs. 3 and 4 are detail views of one of the sprinklers 120 preferably employed; Fig. 5 is a diagram partly in elevation and partly in section of a somewhat modified salt-mining apparatus or plant, also in accordance with the invention, but with some of the improvements omitted, and Fig. 6 is a view of the evaporating chamber and vat of Fig. 5, in vertical 125 130

section at right angles to that of Fig. 5 and with part of said chamber and vat broken away.

The evaporator for the brine-circulating system shown at the right of Figs. 1, 2 and 5 and in Fig. 6 is represented herein, to illustrate first an evaporator adapted for evaporation to be effected therein at the expense of heat stored in the evaporating brine, and second, an evaporator in which such evaporation can be carried on by the exposure to an evaporation-promoting atmosphere of the evaporating brine unsupported in the form of drops.

If the advantages of an evaporation by exposure of the evaporating brine in the form of drops unsupported, should not be desired, other apparatus may be used in which evaporation can take place at the expense of the heat stored in the evaporating brine, without the aid of said exposure. An open pan or series of open pans in a well ventilated building; with an ordinary supply pipe, or a vacuum pan with a similar supply pipe and without a heating belt (or with a heating belt if the vapor tension in the brine chamber would be less than corresponds with the temperature of the entering brine) would serve as such apparatus. Other known or suitable forms of evaporator for evaporating at the expense of the heat stored in the brine or other liquid previous to the evaporation (with or without exposure in drops) may be used. The closed evaporator and heaters shown are to exhibit by way of example suitable forms of a closed evaporator and steam heaters respectively. Other known or suitable forms of such evaporator and heaters may be used, also an open evaporator.

Referring to Figs. 1-4, the evaporator for the brine circulation consists, as shown, of a chamber 21 in the form of a large room, supplied with air through the ducts 23 by the air-inducting fans, 24, and provided with sprinklers in the form of nozzles 26 (see Figs. 3 and 4) with spatter plates 27 in front of their jet orifices 28. The air escapes at the top of the chamber. The sprinklers are mounted, at opposite sides of the chamber 21, on horizontal pipes 25 which receive brine from the supply pipe *w*, through the horizontal branches 251 and the upright branches 250. The pump 88 delivers the brine through the pipe *q*, the surface condensing steam heater *r*, the pipe 808 the surface condensing steam heater 8 and the pipe *w*. It should be delivered into the evaporating chamber 21 under a pressure of from about twenty to thirty pounds to the square inch, through jet orifices 28 which may be about a quarter inch in diameter; so that the jets are broken by striking against the spatter plates 27 into small drops of brine, which are exposed

unsupported in the slowly rising current of air in the chamber 21. The brine may have a higher or a lower temperature; but one of about 145° F. is a good average. With closed heaters the temperature may be 70 above the boiling point of the brine; but such superheating of the brine introduces difficulties; so that it is preferred not exceed the boiling point of the brine. The brine exposed unsupported in small drops to an 75 atmosphere of so much lower vapor tension than the brine (supposing the latter at say 145° F.) is rapidly evaporated, so that during the passage of the drops through the atmosphere of chamber 21 a considerable 80 percentage (say upwards of three per cent.) of the water may be evaporated and the brine correspondingly lowered (say upwards of thirty degrees Fahrenheit) in temperature. Under these conditions the evaporation 85 proceeds faster than the precipitation of the salt in the brine drops and the result is a supersaturated solution of brine with particles of a fine salt therein. So far as the present invention is concerned the nature 90 of the products is immaterial, so long as salt is obtained by the evaporation; and the conditions can therefore be varied as desired; only a large percentage of evaporation is desirable, and when the residual 95 brine, as explained below, is to be used to condense vacuum steam, the cooling caused by the evaporation should be sufficient to reduce the temperature of the brine (not too high when injected) to a suitably low degree. 100

Below the sprinklers 26-27 at the floor of the chamber 21 is a vat 31, divided as shown into compartments by a partition 32 (Fig. 2) and provided with an overflow 33 by which the brine enters the trough 212. The salt 105 liberated in the brine drops, and other salt precipitated out of the brine as it stands in the vat 21 settles to the bottom 310 of the vat. From this it could be fished or raked out, mechanically or by hand in the manner 110 in which salt is removed from the ordinary open pans; but as shown, there is to each compartment of the vat a draw off 35 which is opened when the salt has accumulated to the desired depth and through which the 115 mother brine and salt are removed. The brine flows of itself into the conduit 36, to be thereby conducted into the pit 39 from which it is removed by the pump 398 and delivered through the pipe 399 to the trough 120 212 above referred to. The salt is washed out by a stream of brine from hose attached to the hose plug 38 which is supplied with brine for the supply pipe *w* through the branch pipe 380. The same or a similar 125 stream carries the salt down the conduit 36 into the pit 39 for which it can be removed by an elevator (not shown) for any desired treatment.

Practically it is considered expedient to 130

separate the salt into grades by sifting; and the coarser particles can be ground if desired. These things, including the mode of and means for removing the salt from the 5 vat 31 are outside of the present invention. The waste brine from the pit 39 can be pumped into the trough 212 by pump 398 through pipe 399. It may also be observed that the brine from the vat 31 if not 10 reduced by its repose therein from the condition of supersaturation to that of ordinary saturation, can be allowed further to precipitate salt in other receivers before it is conveyed to the pump 88; and that to avoid 15 difficulties of salt incrusting the pumps, the brine to be pumped can be heated with dry heat or by an injection of steam so as to be a little below saturation.

The heaters *r* and 8 are each composed of a 20 vessel divided by tube sheets, with numerous open ended tubes *a* between them, so as to form two chambers, one of which includes the spaces inside the said tubes and the other the space outside the same, as common in tubular heaters. As shown each of these 25 chambers has a valved brine inlet *h* and a valved brine outlet *p*, so that from pipe *q* or 808 the brine may pass through either chamber of the heater *r* or 8 according to which 30 the passages *h* and *p* of the corresponding heater may be opened. Each heater has a valved steam inlet *f* and a valved outlet *g* for the water of condensation. When the brine is passing through one of the chambers of a 35 heater (*r* or 8) the steam is admitted to the other chamber; and at intervals the inlets and outlets are changed; so that any calcium sulfate which may have been gradually deposited on the tubes *a* (inside or outside as 40 the case may be) while the brine is passing through or over the same, is gradually dissolved off when the valves are changed and the steam is condensed in contact with the deposit. Should it be desired to use heaters 45 with the brine inlet and outlet for one chamber only, and the steam inlet and water outlet for the other chamber only, they could be used; and the deposits of calcium sulfate could be removed in the ordinary way (boiling 50 with water and scraping).

The heater 8 has its chamber partly divided by two partitions 16 and 17 so that the brine and steam pass upward through or over one half the tubes *a* and then downward 55 through or over the other half; while in the heater *r* they pass in one direction through or over all the tubes. An undivided heater such as *r* could be substituted if desired, for the partitioned heater 8, and conversely. As 60 shown, the heater *r* is to be heated by vacuum steam from the closed evaporator *t*; and to aid in maintaining the vacuum (sub-atmospheric pressure) in said evaporator *t* above the brine therein, the condensed water outlets *g* of said heater *r* are made large in order

to carry off also the uncondensed steam and are connected with an injection condenser *x* supplied with cold water or brine through the injection pipe *y* and provided with a pipe *z* leading to an air pump (not shown) and 70 with a water discharging pipe 10 sealed at the bottom by dipping into a cup and of sufficient length for the hydrostatic column therein to counterbalance the excess of pressure of the outside air due to the vacuum in 75 the vessels *x*, *r* and *t*.

The closed evaporator (vacuum pan) *t* is provided between tube sheets with tubes *a* which divide its interior into two chambers, one composed of the spaces inside of said 80 tubes together with the end compartments *c* and *d* beyond the tube sheets and the other of the space around said tubes. The dome *e* also forms part of this chamber. Each chamber has a valved brine inlet *h*, a valved 85 steam inlet *f*, a valved outlet *k* for the exhaust (vacuum) steam given off for the brine, a valved outlet *l* for withdrawing the salt which precipitates and settles, and a valved outlet *g* for the water of condensation. One of the tubes *a* should be of large 90 diameter for the descent of the brine and salt in the chamber which includes the inside of the tubes and a similar passage should be formed in the chamber which surrounds said 95 tubes *a* by omitting enough of these to leave a suitable passage. When one of the chambers is charged with brine, the other is receiving steam (say at atmospheric pressure) through pipe *n* from any suitable source (say 100 a closed evaporator heated by steam of super-atmospheric pressure, or a non-condensing engine or other source) and the valves are changed from time to time; so that a chamber which has been charged with brine and 105 whose walls have become gradually incrusted with calcium sulfate from said brine, after an interval is supplied with steam, which condensing in contact with said walls gradually removes the incrustation while imparting 110 heat through said walls (namely the sides of tubes *a*) to the brine which has been introduced into the chamber which was filled with steam before the valves were changed. Should it be desired to use a closed evaporator 115 (vacuum pan) with valved passages for the brine and its products (exhaust steam and salt) for one chamber only, and with valved passages for the steam and its product (water of condensation) for the other chamber only, the same can be used; and the calcium sulfate can be removed from time to time by boiling out and scraping the tubes *a* in the well known manner.

As shown the heater 8 is to be supplied 125 through the pipe 99 and one or other of the steam inlets with exhaust steam for the engine 858, at atmospheric pressure (212° F. temperature). This engine is to be taken as a representative of whatever engine or en- 130

gines may be available, including those for pumping and driving the fans 24 and the like.

The water of condensation from the heater 5 *r* is conveyed by the pipe 400 provided with a trap at the bottom and made of such vertical length as to support a column which will balance the excess of pressure of the air over the sub-atmospheric pressure (vacuum) in the 10 heater *r*. The pipe 401 receives water of condensation from the heater *r* through said vertical pipe 400; and it also receives the water of condensation from the heater 8 (through the pipe 402) and from the closed 15 evaporator *t* (through the pipe 403). The pipe 401 opens into the inlet pipe 424 of the pump 406 which discharges the water from said pipe 401 through the casing 407 and well bore into the underground salt deposit 408. 20 While in the said deposit, it speedily dissolves salt to a larger amount and all the more speedily on account of the elevated temperature of the water. Holding in solution the salt which it has dissolved in the deposit 25 408, it rises through the tubing 409 and is delivered by the pump 410 through the pipe 411 into the pipe *w* which supplies the sprinklers 26—27 and through the pipe 412 to the closed evaporator *t*. As thus far described therefore, there is first the circulation above ground of brine through the sprinklers 26—27, chamber 21, vat 31, trough 212, pump 88, pipe *q*, heater *r*, pipe 808, heater 8, pipe *w* and the branch pipes 251, 250 and 25 35 to the sprinklers 26—27, (second) the generation from another body of brine, in one of the chambers of the closed evaporator *t*, of vacuum steam which is supplied through the pipe *w* to the heater *r* for raising the temperature of the brine of the above mentioned 40 circulation, (third) the supply from a source not shown of steam of (say) atmospheric pressure to the closed evaporator *t* for boiling the aforesaid brine in the vacuum chamber 45 thereof, (fourth) the delivery from an engine 858 of exhaust steam of atmospheric pressure through the pipe 99 to the heater 8, (fifth) the delivery to the underground salt deposit 408, through the pipes 400, 402 and 403, pipes 50 401 and 424 pump 406, casing 407 and well (or mine) bore of the hot water from the condensation of steam which has become condensed in imparting its heat in the heaters *r* and 8 to the brine of said circulation and in 55 the closed evaporator *t* to that of said other body of brine, and (sixth) the replenishing of the said circulation and the said other body with hot brine formed in said deposit 408 by the water from said condensation of steam 60 and supplied through the tubing 409, pump 410 and pipes 411 and 412.

Instead of replenishing the body of brine in the closed evaporator *t* directly from the brine which is coming from the mine, all the 65 brine from the mine could be delivered into

the circulation and the closed evaporator *t* be replenished from the brine of said circulation. The closed evaporator would still, however, in that case be supplied with brine from the mine; and the fact that it for a greater or less time formed part of the said circulation would not be material. Whether taken directly or indirectly from the mine, the relation of the temperature at which the brine is delivered into the evaporator *t* to that of the evaporating brine therein affects somewhat the role of the heat in said brine. If the entering brine be no hotter than the said evaporating brine, then the heat in said entering brine promotes evaporation simply by lessening the quantity of heat required to raise it to the evaporating temperature; but if it be hotter, then not only is no heat required to raise it to the evaporating temperature, but evaporation takes place at the expense of the heat previously stored in the entering brine, its sensible heat above the evaporating temperature being converted into latent heat of the vapor or steam.

The brine from the mine (deposit 408) being at about the temperature of that from the heater 8 can most advantageously be introduced into the circulating brine on its way to the sprinklers 26—27; but it could be introduced at any desired point. It could be exposed by appropriate sprinkles to the atmosphere of the chamber 21 or of another like chamber before it is allowed to mingle with the circulating brine. It is immaterial whether the water of condensation descends through the casing and bore or through the tubing, (the brine in the latter case rising through the bore and casing or through a second line of tubing).

The heaters 414 and 415 are formed each of an upright vessel provided with a steam inlet connected with piping 416 and 417 respectively at the bottom, with a brine inlet connected with pipes 418 and 419 respectively at the top, and provided with baffle plates 420 and 421 within the vessel for bringing the steam and brine into intimate contact with each other. The brine inlet is shown in each vessel as terminating in a rose for sprinkling. The baffles are shown as 11 consisting of rings 420 and circular plates 421 alternating therewith.

The steam pipe 416 (as shown) is a branch of the pipe 99 and serves to supply exhaust steam from the engine 858 at atmospheric pressure to the heater 414, while the steam pipe 417 is connected with the exhaust steam outlet *k* of the closed evaporator *t* and supplies vacuum steam to the heater 415. The brine pipes 418 and 419 (as shown) are 12 branches of the pipe 422 which is a branch of the discharge pipe *q* of the pump 88. When therefore brine is pumped into the tops of the vessels 414 and 415, it becomes heated (and diluted) in passing through said 13

vessels by meeting and condensing the rising steam. The heated brine from the heater 415 could be pumped into the heater 414, (in place of the brine directly from the pipe *q* or in addition thereto); but as shown the outlet of heater 415 is connected with the inlet pipe 424 of the pump 406 by a long leg 423 (that is by a pipe 423 of sufficient vertical length for a column of water therein to balance the pressure of the air in excess of that inside of the heater 415). The leg or pipe 423 is sealed at the bottom, being provided with an upward bend and entering the bottom of said inlet pipe 424. The outlet pipe 425 of the heater 414 is connected with the same pump inlet 424.

By opening the proper stop cocks, more or less of the residual brine from the trough 212 may therefore be forced by the pump 88 through pipe *q*, pipe 422, branch pipes 418 and 419, heaters 414 and 415, pipes 423 and 425, pipe 424, pump 406, casing 407, well bore in continuation of said casing, deposit 408, tubing 409, pump 410, pipe 411, pipe *w*, and branch pipes 251, 250 and 25 to the sprinklers 26—27. In passing through the heaters 414 and 415, the brine is raised in temperature partly by the heat of the vacuum exhaust steam from the closed evaporator *t* and partly by the exhaust steam at atmospheric temperature from the engine 858, while at the same time the condensed water from said steam passes to the deposit 408 with the brine which has been heated in condensing said steam, and forms brine to replenish the supply of brine in the circulation through the chamber 21, and also the body of brine in the closed evaporator *t*, the said circulation now including the underground salt deposit 408 instead of being outside said deposit like the circulation before described. The supply of replenishing brine is further increased by the brine which is formed in the deposit 408 by the water of condensation from the closed evaporator *t* and (if one or both the heaters *r* and 8 are running) by the brine which is formed by the water of condensation from one or both the heaters *r* and 8. By shutting off the heaters *r* and 8, the circulation can be established wholly through the underground deposit.

After the casing 407 has been driven, the well bored into a salt deposit, the tubing 409 inserted and the pipes connected with said tubing and the casing head respectively, it is most advantageous to supply the hot water of condensation, without admixture with brine; because a given weight of salt dissolves more quickly therein than in partly saturated brine. After a time, the cavity in the mine (deposit 408) so increases that the greatest rapidity possible in dissolving the salt is of less importance; because the solvent liquid will remain anyhow in the deposit a sufficient time for a lower degree of dissolv-

ing capacity to produce saturation. In such case brine can with advantage be allowed to enter the mine (deposit 408) with the water of condensation. As shown there is a branch pipe 430 by which brine from the pipe *w* can be admitted to the inlet of the pump 406 in proper proportion to the size of the cavity, until finally the stop cock in the pipe *w* between the heater 8 and the junction of pipe *w* with the pipe 411 being closed, the whole body of residual brine can be delivered to the pump 406 to be introduced into the deposit 408. It is however, ordinarily as advantageous to heat the brine by direct condensation of steam therein; provided the diluted brine can be supplied to the deposit 408; and for securing such advantages the residual brine, in any desired part or in whole, can be passed through the heaters 414 and 415.

It should be observed that when the brine circulation includes salt deposit 408, said brine can dissolve salt independent of its dilution by the water of condensation; because its temperature in the deposit will be higher than it was in passing through the pump 88; and the solubility of salt in water is increased somewhat by rise of temperature; and that the amount of salt which is dissolved by reason of such higher temperature is clear gain since it can be deposited simply by the reduction in the temperature which the brine undergoes in any event in the chamber 21 and vat 31. There are, however, as before stated, some advantages peculiar to the above ground circulation, which may, as in opening 100 a new deposit, more than compensate for this economy.

Apart from the economy of getting rid of the troublesome removal of calcium sulfate incrustation in the old way, there is also a certain special economy in using surface condensing heaters and evaporators wherein the removal of the calcium sulfate incrustations is effected by the condensation of the steam in contact therewith; because the water of condensation is then charged with calcium sulfate and when introduced into the deposit 408 does not dissolve so much as it otherwise would. Should it be desired to obtain exhaust steam at atmospheric or even at super-atmospheric pressure from the evaporator *t*, this can be obtained by heating said evaporator with steam of appropriate superatmospheric pressure. In such case, the jet condenser *x* and its appurtenances would be unnecessary.

The closed evaporator could of course be dispensed with, the corresponding heater (which uses the exhaust steam from the said evaporator) being dispensed with or being supplied with steam from another source.

Referring to Figs. 5 and 6, the evaporator for the brine circulation is modified by placing the sprinklers 26—27 at the lower part of the chamber 21, and by placing the air in-

ducting fan 24 and its air duct 23 at the top of said chamber. Either of these modifications could be used without the other. At 105 is a trough to catch the drip from the 5 sloping sides of the partition 404, which forms is the bottom of the air duct 23. The air enters at the windows 210 and is forced further inwards by the deflectors 211. In these 10 figures another form of surface condensing 15 heater is shown for the circulating brine; and the closed evaporator, and the heaters using 20 vacuum steam are omitted. When using surface condensing heating, the pump 128 delivers the residual brine from the trough 25 212 through the pipe 110 into the left hand vessel of a series of three vessels, each 30 containing a steam drum 118 provided with open ended tubes for the circulation of the brine through them. Being somewhat raised 35 in temperature, the brine flows through the pipe 119 into the middle vessel wherein it is still further heated, and then through the pipe 120 into the right hand vessel, from 40 which the hot brine is supplied through the pipe 117 to the pump 176 for delivery 45 through the pipes 177 and 178 to the sprinklers 26—27. When desired however, the hot 50 brine can be delivered from the pipe 117 through the pipe 129 and pipe 126 to the pump 406, for introduction into the salt 55 deposit 408 through the casing 407 and well bore in continuation thereof. From either or both the engines 858 (an additional one is shown at the left of Fig. 5 connected by pipe 60 909 with the pipe 99) exhaust steam at atmospheric pressure passes through the pipe 99 into the right hand drum 118 and thence in succession through the other drums of the series, the steam being condensed as it proceeds. The drums are shown as connected at 65 top by the pipes 122 and 124, for the passage of the steam, and at bottom by the pipes 123 and 125 for the passage of the water of condensation. This water escapes by the pipe 126 to the pump 406 which discharges it into 70 the deposit 408 with or without brine from the pipe 129 or from the heater 415 or both, according to the manner of working.

The hot brine from the mine (deposit 408) 75 is delivered by the tubing 409 and the pipe 413 to the pipe 117 which supplies the pump 176 already mentioned. At 115 is a safety valve for each engine. Between each of the pipes 113, which supplies the steam to the 80 corresponding engine 858, and the pipe 99 or 909 for the exhaust steam is shown a by-pass 85 114 (found also in Figs. 1 and 2) for enabling (on occasion) live steam to be used for heating.

For heating the circulating brine by direct 90 condensation of steam therein, a heater 414 is shown of the same construction as in Figs. 1 and 2. It is supplied with brine through pipe 417 from the pipe 110, and with steam 95 through a pipe 416 from the pipe 909 which

can receive steam from either of the engines 858. The heated and diluted brine passes by pipe 425 to the pump 406. At 176 is an escape for any uncondensed steam.

In my applications No. 736,842 and No. 70 737,843, both filed November 13, 1899, I have described and claimed improvements, which (as so described) embody features that are also described herein or that may to some extent be suggested by what is herein 75 described. These features, however, concern only the separation of common salt or like substance from solution; while the claims herein are all of them limited to processes which include as essential coöperating parts 80 both the formation of a solution as specified in the respective claims and the separation of the common salt or like substance from the so formed solution. The improvements claimed in my said applications No. 736,842 85 and No. 736,843 can be used and are designed (when so desired) to be used otherwise than in carrying out the processes claimed herein; which latter constitute, in fact, a distinct subject of invention. 90

I claim as my invention or discovery.—

1. The method of recovering salt or like substance from a natural deposit, by circulating outside of the deposit a stream of brine which is heated at a suitable point in the circulation, introducing an aqueous solvent liquid at super-atmospheric temperature into the salt deposit, removing the brine formed by the solvent action of said liquid still at super-atmospheric temperature, separating salt 95 out of solution by an evaporation at the expense of heat stored partly in the brine from the salt deposit and partly in the brine circulating outside, and uniting the two brines, substantially as described. 100

2. The method of recovering salt or like substance from a natural deposit, by circulating outside of the deposit a stream of brine which is heated at a suitable point in the circulation, introducing an aqueous solvent 110 liquid at super-atmospheric temperature into the salt deposit, removing the brine formed by the solvent action of said liquid still at superatmospheric temperature, separating salt out of solution by the exposure 115 of the heated brine from the said deposit and of the outside circulation unsupported in drops to an evaporation-promoting atmosphere in such manner as to effect an evaporation at the expense of heat stored partly in 120 the brine from the salt deposit and partly in the brine circulating outside, and uniting the two brines, substantially as described.

3. The method of recovering salt or like substance from a natural deposit, by circulating outside of the deposit a stream of brine which is heated at a suitable point in the circulation, introducing an aqueous solvent liquid comparatively free from salt and at superatmospheric temperature into the salt 125 130

- deposit, removing the brine formed by the solvent action of said liquid still at superatmospheric temperature, separating salt out of solution by an evaporation at the expense of heat stored partly in the brine from the salt deposit and partly in the brine circulating outside, and uniting the two brines, substantially as described.
4. In recovering salt or like substance from a natural deposit by means of an aqueous solvent, the improvement consisting in introducing water comparatively free from salt after a working volume of brine has been secured while the cavity in the deposit is comparatively small, and when the cavity is larger introducing water holding a larger proportion of salt in solution and formed of brine heated and diluted by direct condensation of steam therein, substantially as described.
5. In recovering salt or like substance from a natural deposit by means of an aqueous solvent, the improvement consisting in introducing water comparatively free from salt and at superatmospheric temperature when the cavity in the deposit is comparatively small, and when the cavity is larger introducing water holding a larger proportion of salt in solution and formed of brine heated and diluted by direct condensation of steam therein, the salt being separated from the brine from the deposit by an evaporation at the expense of heat stored in the said brine previous to its removal from the deposit, and the heated and diluted brine introduced into the deposit being residual brine from said evaporation, substantially as described.
6. The method of recovering salt or like substance from a natural deposit, as follows: that is to say, when the cavity in the deposit is comparatively small effecting the surface condensation of steam by means of residual brine hereinafter referred to and introducing into the deposit the water from said surface condensation at superatmospheric temperature, when the cavity in the deposit becomes larger heating and diluting residual brine hereinafter referred to by direct condensation of steam therein and introducing the so-heated and so-diluted brine to said deposit, and in both stages removing the brine at superatmospheric temperature and separating the salt therefrom by evaporation at the expense of heat stored in said brine previous to its removal from the deposit, so as to leave residual brine to serve for the surface or the direct condensation of steam hereinabove mentioned, the water from the surface condensation and the heated and diluted brine from the direct condensation being both introduced if desired yet in such manner that the brine of greater strength be introduced when the cavity is larger, and the residual brine heated by surface condensation being subjected to evaporation as aforesaid and

united with brine from the deposit, substantially as described.

7. The method of recovering salt or like substance from a natural deposit, by raising the temperature of a stream of residual brine circulating outside of the deposit by the surface condensation of steam, introducing into the deposit an aqueous solvent at superatmospheric temperature composed of the water from said condensation, removing the brine from the deposit at superatmospheric temperature, separating salt by an evaporation at the expense partly of the heat stored in the brine from the deposit previous to its removal therefrom and partly of the heat stored in the residual brine by the said surface condensation of steam, and uniting brine from the deposit to the circulating stream of residual brine, substantially as described.

8. The method of recovering salt or like substance from a natural deposit, by raising the temperature of a stream of residual brine circulating outside of the deposit by the surface condensation of steam, introducing into the deposit an aqueous solvent at superatmospheric temperature composed of the water from said condensation, removing the brine from the deposit at superatmospheric temperature, separating salt by the exposure of the heated brine from said deposit and of the outside circulation unsupported in drops to an evaporation-promoting atmosphere in such manner as to effect an evaporation at the expense partly of the heat stored in the brine from the deposit previous to its removal therefrom and partly of the heat stored in the residual brine by the said surface condensation of steam, and uniting brine from the deposit to the circulating stream of residual brine, substantially as described.

9. The method of recovering salt or like substance from a natural deposit, by raising the temperature of a stream of residual brine circulating outside of the deposit by the surface condensation of steam, introducing into the deposit an aqueous solvent at superatmospheric temperature comparatively free from salt and composed of the water from said condensation, removing the brine from the deposit at superatmospheric temperature, separating salt by an evaporation at the expense partly of the heat stored in the brine from the deposit previous to its removal therefrom and partly of the heat stored in the residual brine by the said surface condensation of steam, and uniting brine from the deposit to the circulating stream of residual brine, substantially as described.

10. The method of recovering salt or like substance from a natural deposit by raising the temperature of a stream of residual brine by the surface condensation of steam, introducing into the deposit an aqueous solvent

at superatmospheric temperature composed partly of water from said condensation and partly of said residual brine, removing the brine from the deposit at superatmospheric 5 temperature, and separating salt by an evaporation at the expense of heat in the brine from the deposit at the time of its removal therefrom, substantially as described.

11. In recovering salt or like substances 10 from a natural deposit by an aqueous solvent, the improvement consisting in introducing water comparatively free from salt after a working volume of brine has been secured while the cavity in the deposit is comparatively 15 small, and when the cavity is larger introducing water holding a larger proportion of salt in solution, substantially as described.

12. The method of recovering salt or like 20 substance from a natural deposit, by transferring heat to a body of brine through heat-conducting wells from steam which is condensed to water by such transfer of its heat, introducing the said water of condensation 25 at superatmospheric temperature into the salt deposit, removing it therefrom after it has dissolved the salt in the deposit and while still at superatmospheric temperature, separating salt from the first mentioned body 30 of brine by an evaporation which is promoted by the heat transferred thereto from the said steam, and replenishing the said body of brine by brine from said deposit, while it still holds heat which the said water 35 of condensation retained from the said steam, substantially as described.

13. The method of recovering salt or like 40 substance from a natural deposit, by evaporating a body of brine by heat transferred thereto through heat-conducting walls from steam which is condensed to water by such transfer of its heat, evaporating a second body of brine by heat transferred thereto from the steam which arises from the first 45 mentioned body of brine and which is condensed to water by such transfer of its heat, introducing the hot water condensed by each of said bodies of brine into the salt deposit, removing the brine formed in the de- 50 posit by the dissolving action of said water, and replenishing both said bodies of brine by brine from said deposit while it still holds heat which the water of condensation retained from the said steam, substantially as 55 described.

14. The method of recovering salt or like 60 substance from a natural deposit, by evaporating a body of brine by heat transferred thereto through heat-conducting walls from steam which is condensed to water by such transfer of its heat, circulating a second body

of brine, transferring heat thereto at one point of its circulation from the steam which arises from the first mentioned body of brine and which is condensed to water by such 65 transfer of its heat, exposing the so-heated brine at another point of its circulation to an evaporation-promoting atmosphere, introducing the hot water condensed by each of said bodies of brine into the salt deposit, removing the brine formed in the deposit by the dissolving action of said water, and replenishing both said bodies of brine by brine from said deposit while it still holds heat which the water of condensation retained 75 from the said steam, substantially as described.

15. The method of recovering salt or like substance from a natural deposit, by circulating a body of brine, exposing it at one 80 point of the circulation unsupported in small drops distributed throughout a large room filled with an evaporation-promoting atmosphere in such manner as to reduce the residual brine suitably below 135° F., raising 85 its temperature at another part of its circulation by the transfer thereto of the heat from vacuum steam which is condensed to water by said transfer of its heat, introducing the said water of condensation at superat- 90 mospheric temperature into the salt deposit, and replenishing said body of brine in circulation with brine from said deposit while the latter still holds heat which said water of condensation retained from said vacuum 95 steam, so that the evaporation of said first mentioned body of brine is at the expense of the so-retained heat still present in the brine, substantially as described.

16. The method of recovering salt or like 100 substance from a natural deposit, by transferring heat to a body of brine through heat-conducting wells by steam which is condensed to water by such transfer of its heat, separating salt from said brine by an evap- 105 oration which is promoted by the so-transferred heat, reversing the respective positions of the brine and steam relative to the said heat-conducting walls, introducing the water of condensation charged with calcium sul- 110 fate from the incrustation left on said walls by the brine into the deposit of salt or like substance, and replenishing the said body of brine by means of the brine formed by the dissolving action of the said water in said 115 deposit, substantially as described.

In testimony whereof I affix my signature, in presence of two witnesses.
